MACHINE FOR USE IN ATTACHING SOLES
TO SHOESHelge Gulbrandsen, Beverly, Mass., assignor to
United Shoe Machinery Corporation, Flemington, N. J., a corporation of New Jersey

Application June 5, 1946, Serial No. 674,468

28 Claims. (Cl. 12—1)

1

This invention relates to machines for cement-attaching soles to shoes, and particularly to apparatus for conditioning soles prior to attachment to shoes and for presenting them to the operator at the proper time and in the proper condition for the sole attaching operation. This application is a continuation-in-part of my application Serial No. 556,333, filed September 29, 1944 (now Patent No. 2,435,582, granted February 10, 1948).

Objects of the invention are to facilitate the practice of the method disclosed in United States Letters Patent No. 2,373,922, granted April 17, 1945, upon an application of Max W. Tetlow.

The illustrated machine provides improved apparatus comprising a cabinet for treating at one time a plurality of soles with hot vapor-laden air both to temper the soles and to activate the cement thereon, the cabinet being, for example, arranged adjacent to a sole-attaching machine of the eight-station turret type similar to that disclosed in Letters Patent of the United States No. 2,047,185, granted July 14, 1936, on application of Milton H. Ballard et al.

Manually operated means is provided for ejecting soles from the cabinet one after the other.

It is desirable at times, as for example when the sole conditioning apparatus is not used in conjunction with a sole attaching machine, to incorporate the conditioning apparatus in a separate machine. Accordingly, in accordance with a feature of my invention, a form of sole ejecting means is illustrated by way of example which is independent of the operation of a sole attaching machine. As shown, the ejecting means consist of an operator controlled system which is directly connected to the sole ejecting mechanism so that soles can be ejected independently of the operation of an associated machine.

The illustrated cabinet has in its upper part stalls for holding soles supported on edge and the sides of the stalls, which may contact with one or the other of the faces of the sole, are made of heat-insulating material such as wood so that condensation of moisture thereon will be minimized and transference of condensed water to the face of the sole avoided.

To reduce the relative humidity of the activating and tempering atmosphere of the cabinet, means is provided for introducing air into the cabinet above the water level, the arrangement being such that the amount of air may be varied to control the humidity of the atmosphere.

To maintain a constant level of water in the cabinet and gradually to restore the water as it

is evaporated, a pocket is provided on the side of the cabinet which is continually supplied with cool water and maintained at a constant level by an overflow pipe, the pocket having a restricted passage leading to the cabinet whereby the water level in the cabinet is maintained the same as that in the pocket.

In order that the water in the cabinet may be heated quickly in starting the apparatus, the bottom of the cabinet is provided with a well in which the heating element is located, the water spreading out above the well to provide an adequate surface for evaporation.

These and other features of the invention will appear more fully from the following description when read in connection with the accompanying drawings and will be pointed out in the appended claims.

In the drawings,

20 Fig. 1 is a front view in perspective of a so-called eight-station sole-attaching machine of the type disclosed in the Ballard et al. patent above referred to, equipped with the apparatus of the present invention, the pad, gages and pressure-applying mechanism at the operating station being shown in full, and the two adjacent identical pads, gages and pressure-applying mechanisms being shown in outline;

25 Fig. 2 is a plan view of the activating cabinet and the shoe carrier or turntable mounted on a sole-attaching machine of the type referred to;

30 Fig. 3 is a front elevation of the activating cabinet and the shoe-carrying turntable;

Fig. 4 is a longitudinal sectional view of the 35 cabinet showing the sole-ejecting mechanism;

Fig. 5 is a plan view of the sole-holding rack with which the cabinet is provided;

Fig. 6 is a plan view of the cabinet with the cover raised;

40 Fig. 7 is a sectional detail showing the connections for supplying water to the base of the cabinet and maintaining a constant level of water therein;

Fig. 8 is a rear elevation of the sole-ejecting 45 mechanism;

Fig. 9 is a perspective view of parts shown in Fig. 8;

Fig. 10 is a plan view of the air and water pumps at the base of the machine; and

50 Fig. 11 is a schematic view showing a treadle controlled system directly connected to the sole ejecting mechanism.

Referring to Fig. 2, the numeral 10 indicates a shaft about the center of which the turret 55 250 of the sole-attaching machine rotates, sev-

eral of the cylinders carried by the turret and by which pressure is applied to the shoe and sole being shown at 12. A shoe-carrying turntable 14 (Fig. 3) has a hub 16 which is journaled in a stud 18 mounted in a bracket 20 fixed at one end to the shaft 10 at the center of the turret of the machine and at the other end to a shelf 24 on which an activating cabinet 26 is mounted. The turntable 14 and the cabinet 26 are arranged at about breast height so the operator can conveniently reach them.

On the turntable 14 are five blocks 30 having surfaces 32 downwardly and outwardly inclined at about 30° to the horizontal and to each of these surfaces are attached curved strips 34 arranged to form a tray to receive a shoe. The cabinet 26 is an improvement over that disclosed in Letters Patent of the United States No. 2,334,232 granted November 16, 1943, upon the application of Adoniram J. Wells. The cabinet 26 consists of a metallic casing 40 (Fig. 4) preferably covered with a thick layer of insulating material 42 and having a hinged cover 44 held closed by a screw 46. In the cover is a chimney 48 having a damper 50 to control ventilation through the chimney. In the front of the casing (Fig. 3) is a series of four slots 51, 52, 53 and 54 through which soles 50 may be introduced into the upper part of the cabinet toe end first.

The soles are supported on their edges in a removable cage comprising an upper rectangular frame 60 (Fig. 4) and a similar lower rectangular frame 62, the frames being connected at their ends by vertical struts 64. Arranged longitudinally of the frames and supported at their ends in the struts 64 are dowel-like rods 66 (Fig. 5) of non-heat-conducting material such as wood, arranged to form four stalls 71, 72, 73 and 74 to receive soles, the front ends of the stalls being positioned opposite the slots in the casing. As indicated in Fig. 4, each side of each stall is formed by four of the rods 66 supported at their ends in the vertical struts 64.

The edges of the foreparts of the soles rest on a series of transverse rods 76 supported at 45 their ends in the lower frame 62 and the rear ends of the soles rest on a wire mesh 78 which facilitates sliding of the soles lengthwise of the stalls. The lower frame 62 of the cage rests on screw studs 80 projecting inwardly of the casing and is held in place by hooks 82 engaging the sides of the upper frame 60 and serving to hold the cage from lateral movement with the stalls aligned with the slots.

In front of the slots (Figs. 1 and 3) is a canvas curtain 84 which covers the upper parts of the slots, the curtain being slit at 86 centrally of the slots and the edges bound with durable flexible material such as leather. The soles are readily insertable into the cabinet through the slits in the curtain.

Compressed air is supplied by a pipe 90 entering through the side of the cabinet (Fig. 6) connected first to a pipe 92 extending around the periphery of the cabinet near the wall and below the soles. The pipe 92 is perforated at intervals in its upper sides by holes 94 which allow air to pass upward into the sole-treating chamber. The pipe 90 is connected to a vertical pipe 96 (Fig. 4) having therein a restricted passage 98 which allows part of the air to pass to a series of connected pipes 100 which are perforated on their lower sides and are partially immersed in water contained in the lower part of the cabinet. The water level is indicated at 102 (Fig. 3), and

running lengthwise of the bottom of the cabinet is a depression or well 104 in which is an immersion heater 106 supplied with current from a junction box 108 on which is a light 110 which glows when the current is on. The current is controlled by a thermostat 112 which is adjusted to maintain the water at a predetermined temperature by turning a knob 114, the setting being indicated by movement of a pointer 116 over a temperature scale 118. The temperature of the vapor-laden air in the cabinet is indicated by a thermometer 120 located (Fig. 4) a short distance below the pipe 92.

Between the pipe 92 and the thermometer 120 is a solid baffle plate 122 which extends nearly to the walls of the cabinet but is spaced therefrom at 124 enough to allow circulation of the vapor-laden air around its edges up into the sole-treating chamber. Spaced downwardly from the baffle plate 122 is another plate 126 which, as shown in Fig. 6, has a large piece removed from its rear end, as indicated by the line 128. Below the plate 126 is a third plate 130 which is perforated throughout its extent by relatively large holes 132. These baffles insure that any water in a liquid state will be removed from the hot vapor-laden air before it reaches the sole-treating chamber.

Compressed air is supplied to the pipe 90 by an air pump 140 (Fig. 10) located in the base of the machine and driven by a belt 142 from a suitable motor. The air enters the pump through a suitable strainer 144 and is discharged through the pipe 90 which extends up to the cabinet through a protective casing 146. The pump 140 is supplied with oil by an oil cup 148.

Water is supplied to the bottom of the casing 40 by a rotary pump 150 which receives water through a pipe 154 from a tank 156 and delivers it through a pipe 158 to a chamber 160 (Fig. 7) formed by a pocket 162 secured by screws 163 to the side of the cabinet casing 40 and having a cover 164. An outlet pipe 166 enters the pocket 160 at a slightly higher level than the inlet pipe 158 and conducts the excess of water back to the tank 156. Leakage through the bearing of the pump 150 is led back to the tank by a pipe 168. The pipes 158 and 166 also pass up through the protective casing 146.

The capacity of the water pump 150 is such that the chamber 160 is continuously supplied with cool water and maintained at a substantially constant level by the overflow pipe 166. Communication between the chamber 160 and the lower part of the casing 40 is provided by a small opening 170 (Fig. 7) so that, as the heated water in the casing 40 evaporates, its place will be taken by cool water from the chamber 160 and the level of water in the casing maintained constant. The opening 170 is preferably made by providing a groove in the side of a plug which fits a larger opening and can be removed for cleaning if necessary.

Soles placed in the cabinet for tempering and activation of the cement thereon are ejected seriatim by mechanism best shown in Figs. 2, 4, 8 and 9. A series of rods 171, 172, 173 and 174 project through openings 176 in bosses 178 from the rear end of the casing 40. Each boss is counterbored (Fig. 4) to receive a rubber washer 180 which is held in place by a plate 182, the washers sealing the opening but permitting silent reciprocation of the rods therethrough. At the rear end of each of the stalls 71, 72, 73 and 74 is a pusher 184, the pushers being attached one to

each of the rods 171, 172, 173 and 174, and each acting when its rod is reciprocated to engage the front end of the sole O and push the heel end out of the slot in the front end of the casing far enough so that it can be easily grasped by the operator.

The rods 171, 172, 173 and 174 are reciprocated in turn by the following mechanism. Each rod projects through a block 190 in which it is adjustably secured by a setscrew 192. Each block is pivoted at 194 to a lever, the levers being numbered 201, 202, 203 and 204 (Fig. 8) in the order of the rods. The levers are all pivoted on a shaft 206 mounted in a bracket 208 secured at 210 to the shelf 24 which supports the cabinet. Each lever has a lower arm 212 to which a tension spring 214 is attached, the front end of the spring being secured to an ear 216 on the bracket 208. The tension of the spring holds each lever turned clockwise (Fig. 4) until a projection 218 thereon rests against a stop screw 220 threaded through a portion 222 of the bracket 208.

To operate the levers 201, 202, 203 and 204 in sequence, for example in the order in which they are numbered, a shaft 224 is journaled in bearings 226, 228 formed on the bracket 208 (Fig. 8). At one side of the bearing 228 a collar 230 is pinned on the shaft 224 and at the other side of the bearing is pinned an eight-toothed ratchet wheel 232 (Fig. 4) counterclockwise movement of which is prevented by a leaf spring 234 formed as a pawl engaging the ratchet and secured at 236 to the bearing 228. On the shaft 224 (Figs. 8 and 9) is a series of double-ended tappets 241, 242, 243 and 244 so arranged rotationally on the shaft that when the shaft is given a partial rotation one-eighth of a turn the tappet 241 will engage the arm 212 of the lever 201 and will operate the pusher on the rod 171 to eject the sole in the stall 71 through the slot 51. The next partial rotation of the shaft 224 will cause the tappet 242 similarly to operate the lever 202 and eject a sole from the slot 52. Upon the next partial rotation of the shaft the tappet 243 will eject a sole from the slot 53, and upon the next partial rotation of the shaft the tappet 244 will eject a sole from the slot 54. Then upon the next partial rotation of the shaft the opposite end 241' of the tappet 241 will come into action at the slot 51 and soles will be ejected successively in the named order by the opposite ends 242', 243', 244' of the tappets as they are brought into action by rotation of the shaft 224.

The ratchet wheel 232 is turned one tooth at each indexing of the main turret of the eight-station machine by mechanism shown in Fig. 3. Mounted on the main turret 250 (Fig. 1) in a manner to be described is a series of cam blocks 251, 252, 253, 254, 251', 252', 253', 254', one for each pad box of the machine. In Fig. 4 one of these cam blocks 254' has just been moved in a leftward direction by rotation of the turret 250, the inclined upper face of the cam 254' has engaged a roll 256 on a lever 258 pivoted at 260 to the shelf 24, lifted the lever and caused a pawl 262 pivoted at 264 on the lever to rise, engage a tooth of the ratchet wheel 232 and rotate the wheel and the shaft 224 one-eighth of a turn, the parts being now in position to be operated by the next cam 251 of the series (Fig. 2) which will act upon the next indexing of the turret 250 to operate the pawl 262, in the manner described, to cause the tappet 241 to swing the lever 201 to eject a sole through the slot 51.

The pawl 262 is held by a compression spring 75

266 (Fig. 4) against a stop 268, and the throw of the lever 258 is adjusted by a stop screw 270 against which it rests by gravity.

The cam which operates the tappet 244 is not shown in Fig. 2 but would be halfway between the cams 253 and 251'. The cams 251', 252', 253' and 254' which operate in a similar manner the opposite ends 241', 242', 243' and 244' of the tappets to eject the second series of four soles are clearly shown in Fig. 2.

Each of the eight cams 251, etc., (Figs. 1, 3 and 4) is fixed to an upright 272 which has a cross-piece 274 formed at each end to engage the surface contour of one of the eight cylinders 12 with which the sole-attaching machine is provided, as disclosed in the Ballard et al. patent above referred to wherein the cylinders are indicated by 348. The cross-piece 274 (Fig. 2) is clamped between two of the cylinders 12 by setscrews 276 and is held down by screws 278.

To turn the turntable 14 one-fifth of a revolution in timed relation to the ejection of soles, the cam on each upright 272 has a projection 280 (Fig. 4) on which is an upstanding roll 282 arranged to engage, when the turret turns, a notch 284 in a spider 286 secured to the hub 16 of the turntable 14.

In the position shown in Fig. 1, the cam 253' is visible to the operator at the operating station and may, for his convenience, be permanently marked 1L, the next cam 254' marked 2R, cam 251 marked 3L, cam 252 marked 4R, cam 253 marked 1L again, and so on for the second series of four. This will indicate to the operator that the next pad to come along when he indexes the machine will be for a left shoe and that the sole therefor will be ejected from the first slot (51). When the mark 2R shows, he will know that a right shoe pad is coming along next and that the sole therefor will be ejected from the second slot (52). That is, the letter will indicate whether a left or a right shoe pad comes next, and the number will be that of the slot counting from left to right from which the next sole will be ejected.

In starting the machine, the current for the heater 106 is turned on long enough beforehand to heat the apparatus so that the temperature of the vapor-laden air in the cabinet is about 68° to 70° C. (154° to 172° F.). This will not take long since the well 104 contains only a relatively small quantity of water which surrounds the immersion heater 106. Above the well the water spreads out the full size of the cabinet to provide a large evaporating surface and is only deep enough to at least partially immerse the pipes 100 through the lower sides of which air is being forced. The air, as it bubbles up through the water, is heated and laden with water-vapor nearly to the saturation point; that is, it may have, for example, about 95% relative humidity. In passing up through and around the baffles 130, 126 and 122, any water as such will be removed and in passing around the baffle 122 the vapor-laden air will be mixed with air from the pipe 92 the quantity of which may be controlled by a valve 290 in the pipe 90. As a result, the relative humidity of the vapor-laden air in the chamber may be varied to the desired extent for treating soles in different conditions of temper as they come to the machine.

After the cabinet is heated, the operator places soles in the cabinet and shoes in the trays. Supposing, for example, the cam 253' (marked 1L in Fig. 1) is visible, he places a left sole in the slot 51 of the cabinet and the shoe to which this sole

is to be attached in the tray A. A right sole is then placed in the slot 52 and the shoe in the tray B. A left sole is placed in the slot 53 and a left shoe in the tray C. A right sole is placed in the slot 54 and a right shoe in the tray D.

After the first sole has been in the cabinet for about thirty seconds, the operator indexes the machine by operating a lever 292, bringing the cam 254 marked 2R to the operating station. With his right hand he takes a shoe from the rack and puts it in the tray E which is now in the position D of the drawing. With his left hand he takes a sole for this shoe from the table and with his right hand removes the partially ejected sole from the slot 51 of the cabinet and inserts the new sole that is in his left hand. He places the ejected sole on a pad 294, closes the gages by depressing a treadle 296 connected to a rod 297 (Fig. 1), and takes the shoe from the tray A which is now at the position E of the drawing, places it upon the sole, applies pressure to the shoe and sole and indexes the machine by operating the lever 292. This causes the second sole to be ejected from slot 52 and presents the shoe in tray B at the operating station. A new shoe is placed in the tray A, now at the right of the operator, and the sole therefor in slot 52 after removing the ejected sole in that slot. The sole taken from slot 52 is laid on the pad, and the shoe from tray B is attached to it, and so on. After all the eight stations are filled, the cam marked 1L will again be visible at the operating station and the operator knows that the station to be presented by the next indexing movement will be the one with which he started. Accordingly, he indexes the machine and the first shoe treated is released as it arrives at the operating station. He removes the completed shoe, places it in the rack and takes a new left shoe from the rack, places it in the empty tray and takes a left sole from the table, removes the sole ejected from the slot 51, places the new left sole in its place, puts the ejected sole upon the pad and attaches it to the shoe presented by the tray nearest this station, and so on.

Should it be desired to have the soles in the cabinet for a less time, the operator will first place soles in the slots 51, 52 and 53 and shoes in the trays A, B, and C. Then, after the first sole has been in the cabinet long enough to be activated, he places a new sole in the slot 54 and puts a shoe in tray D. He then indexes the machine, causing the sole to be ejected from the slot 51, which sole he attaches to the shoe in tray A and proceeds as before, introducing a new sole into the empty slot in the cabinet and attaching the ejected sole to a shoe.

It will be desirable under certain conditions to make the operation of the sole conditioning apparatus independent of the operation of the sole attaching machine, as when the apparatus is incorporated in an independent machine so that it can be used in conjunction with attaching machines which are not equipped with a shoe tray such as illustrated herein. A control system for operating the sole ejecting mechanism independently of associated machines is illustrated in Fig. 11 in which the ratchet wheel 232, which is pinned to the tappet shaft 224, is intermittently rotated by a pawl 300 which extends through a guide 302 and is yieldingly held against a stop 304 by a spring 306. The pawl is pivoted at its lower end to a rod 308 which is in turn pivotally connected to a treadle 310, the arrangement being such that each time the treadle is depressed the

pawl 300 is lifted sufficiently to rotate the ratchet wheel 232 and its connected tappet shaft through one-eighth of a revolution.

Having thus described my invention, what I claim as new and desire to secure by Letters Patent of the United States is:

1. Apparatus for treating soles comprising a sole tempering cabinet, fixed stalls within said cabinet for supporting a plurality of soles, means in the cabinet for tempering the soles, and means opposite each stall for successively ejecting the soles individually from the cabinet after they have been tempered, said means being operated by a single treadle.

2. Apparatus for treating soles comprising a cabinet containing hot vapor laden air, a plurality of fixed stalls located side by side in the cabinet, each adapted to support a single sole on its edge, means located opposite each stall for ejecting one sole at a time from the cabinet, and single means for operating all of the ejecting means.

3. Apparatus for treating soles comprising a cabinet containing hot vapor-laden air, a stationary rack, a plurality of stalls above said rack each adapted to support a single sole on its edge in said cabinet, a member in each stall arranged to eject the sole end first from the cabinet, and single treadle operated means for operating said members sequentially.

4. Apparatus for treating soles comprising a cabinet, means for supplying hot vapor-laden air to the cabinet, a plurality of horizontal stalls in the cabinet each adapted to receive only a single sole and to support the sole on its edge, a pusher in each stall for partially ejecting the sole from the cabinet to present it to an operator and single means for operating all of said pushers sequentially.

5. A cabinet for treating a plurality of soles at one time comprising a plurality of stalls located side by side in the cabinet each adapted to support one sole on its edge, means in the cabinet for forming hot vapor-laden air therein, a pusher in each stall for ejecting a sole, a ratchet, a lever between the ratchet and each pusher for operating the pushers in turn, and treadle controlled means for operating the ratchet.

6. Apparatus for use in treating soles to be attached to shoes comprising a cabinet for treating a plurality of soles at one time, means for supplying hot vapor-laden air to the cabinet, a plurality of stalls in the cabinet each adapted to support only one sole at a time on its edge, a pusher in each of the stalls, a ratchet wheel, a plurality of levers operated by the ratchet wheel for actuating the pushers in turn to eject only one sole at a time from the cabinet, and means for turning the ratchet wheel.

7. A cabinet for tempering soles and activating cement thereon comprising a casing having water in the bottom thereof, means for maintaining the water at a constant level, means in the casing for heating the water, and single means for forcing air at room temperature into the cabinet both above and below the water-level.

8. A cabinet for tempering soles and activating cement thereon comprising a casing having a well at the bottom thereof containing a small amount of water, means in the well for heating the water, unitary means for forcing air through the water to heat the air and load it with water-vapor and for simultaneously forcing air into the cabinet above the water, and a rack for supporting soles in the upper part of the cabinet.

9. A cabinet for tempering soles and activating

cement thereon comprising a casing containing hot water in the bottom thereof, means for forcing air at room temperature through the water to heat the air and load it with water-vapor and for introducing air above the water in the cabinet to control the relative humidity of the atmosphere in the cabinet, said air being approximately at room temperature, and a rack for supporting a plurality of soles in the upper part of the casing.

10. A cabinet for tempering soles and activating cement thereon comprising a casing having a well smaller than the casing at the bottom thereof containing a small amount of water which spreads out in the casing above the well, means in the well for heating the water, means for forcing air through the water in the casing to heat the air and load it with water-vapor, means for introducing air at room temperature above the water in the casing to control the relative humidity of the atmosphere in the cabinet, and a rack for supporting soles located in the upper part of the casing.

11. A cabinet for tempering soles and activating cement thereon comprising a casing adapted to receive soles and having water in the bottom thereof, means in the casing for heating the water, perforated pipes having openings therein covered by the water, and single means in the casing for forcing air at room temperature through the pipes to heat the air and produce an atmosphere of vapor-laden air above the water in the casing, said means being constructed and arranged also to introduce unheated air directly into said atmosphere above the water to reduce the relative humidity thereof.

12. A cabinet for tempering soles and activating cement thereon comprising a casing adapted to contain water in its lower portion, means for heating the water, means for forcing air through the water to heat the air and load it with water-vapor, a rack for supporting soles in the upper part of the cabinet, baffle plates between the water and the rack, and means above the baffles for introducing supplementary air to control the relative humidity of the atmosphere in the cabinet.

13. A cabinet for tempering soles and activating cement thereon comprising a rectangular casing adapted to receive soles and having water in the bottom thereof, means for maintaining the water at a constant level, an immersion heater in the water for heating the water, single means for forcing air into the casing both above and below the water level, and means for varying the quantity of air supplied to the casing.

14. A cabinet for tempering soles and activating cement thereon comprising a casing having water in the bottom thereof, mean for heating the water, perforated pipes having openings therein covered by the water, means for forcing air through the pipes to produce an atmosphere of vapor-laden air in the cabinet, and a perforated pipe extending around the cabinet above the water for introducing air directly into said atmosphere to reduce the relative humidity thereof.

15. A cabinet for tempering soles and activating cement thereon comprising a casing adapted to contain water at the bottom thereof, means for heating the water, a rack for supporting soles in the upper part of the cabinet, means for maintaining a constant level of water in the cabinet comprising a pocket mounted on the casing and having communication with a cabinet through a single orifice, means for continuously pumping

water into the pocket, and an overflow pipe for maintaining the water at a constant level.

16. A cabinet for tempering soles and activating cement thereof comprising a casing having a well narrower than the casing at the bottom thereof containing a sufficient amount of water to cover the bottom of the cabinet, means in the well for heating the water, means for maintaining a constant level of water in the cabinet above said well comprising a pocket secured to the casing and, having communication with the cabinet, means for continuously supplying the pocket with water, and an overflow pipe mounted on the pocket for maintaining a constant level of water in the pocket.

17. A cabinet for tempering soles and activating cement thereon comprising a casing adapted to contain water in its lower portion, means for heating the water, means for forcing air through the water to heat the air and load it with water-vapor, a rack for supporting soles in the upper part of the cabinet, baffle plates between the water and the rack, the upper baffle plate being solid and spaced from the casing at its edges, and means above the baffle plates for introducing supplementary air to control the relative humidity of the atmosphere in the cabinet.

18. A cabinet for tempering soles and activating cement thereon comprising a casing adapted to contain water in its lower portion, means for heating the water, means for forcing air through the water to heat the air and load it with water-vapor, a rack for supporting soles in the upper part of the cabinet, baffle plates between the water and the rack, one of said plates having a large notch in its rear end to direct the vapor toward the rear of the cabinet, and means above the baffle plates for introducing supplementary air to control the relative humidity of the atmosphere in the cabinet.

19. An apparatus for tempering soles and activating cement thereon comprising a cabinet for receiving soles, a water container, means for heating the water, means for forcing air through the water to heat the air and load it with water-vapor and for introducing air into the vapor-laden air to control the relative humidity thereof, and operator-controlled means for ejecting one sole at a time from the cabinet.

20. An apparatus for tempering soles and activating cement thereon comprising a cabinet for supporting a plurality of soles, a container for water communicating with said cabinet, means in the container for heating the water, means for forcing air through the water to heat the air and load it with water-vapor, means for ejecting the soles successively from the cabinet, and single operator-controlled means for operating said ejecting means.

21. An apparatus for tempering soles and activating cement thereon comprising a cabinet, a rack in the cabinet for supporting a plurality of soles, a well in the bottom of the cabinet containing water, means for heating the water, means for forcing air through the water to heat the air and load it with water-vapor, said means acting also to add air to the vapor-laden air in the cabinet to control the water-vapor content thereof, and operator-controlled means for sequentially ejecting the soles one at a time from the cabinet.

22. An apparatus for tempering soles and activating cement thereon comprising a cabinet for receiving and supporting a plurality of soles, a water container communicating with said cabinet, means for heating the water, single means for

forcing air through the water to heat the air and load it with water-vapor and for simultaneously introducing air into the vapor-laden air in the cabinet to control the relative humidity thereof, means for each sole for ejecting the soles one at a time from the cabinet, and manually controlled means separate from each sole ejecting means for actuating each ejecting means.

23. An apparatus for tempering soles and activating cement thereon comprising a cabinet adapted to receive a plurality of soles in its upper portion, said cabinet containing water in its bottom portion, means for maintaining the water at a constant level, means in the cabinet for heating the water, means for forcing air through the water to heat the air and load it with water-vapor, means for ejecting the soles from the cabinet, and single manually controlled means separate from the ejecting means for operating said ejecting means sequentially to eject the soles one at a time from the cabinet.

24. An apparatus for tempering soles and activating cement thereon comprising a cabinet consisting of a casing having a depression in its bottom surface for holding water, a plurality of stalls in the upper portion of the cabinet for receiving soles, means in said depression for heating the water, means for forcing air through the water to heat the air and load it with water-vapor, means for introducing air at room temperature into the casing above the water to control the relative humidity of the atmosphere in the cabinet, and operator-controlled means for ejecting the soles from said stalls sequentially and one at a time.

25. An apparatus for tempering soles and activating cement thereon comprising a cabinet adapted to receive and support a plurality of soles, a water container connected to the cabinet, means for heating the water, means for forcing air through the water to heat the air and load it with water-vapor, means including a lever for each sole for ejecting each sole from the cabinet, and single operator-controlled means for actuating each of said levers successively.

26. An apparatus for tempering soles and activating cement thereon comprising a cabinet, means for supporting a plurality of soles in the cabinet, a water receptacle, means for heating the water, means for forcing air through the water to heat the air and load it with water-vapor, a pusher for ejecting each sole from the cabinet, a ratchet, levers between the ratchet and the pushers for operating the pushers, and treadle-controlled means for operating the ratchet to actuate said levers successively.

27. An apparatus for tempering soles and ac-

tivating cement thereon comprising a cabinet, means in the cabinet for supporting soles on their edges, a water receptacle, means for heating the water in the receptacle, means for forcing air through the water to heat the air and load it with water-vapor, pushers in the cabinet, levers connected to the pushers, a shaft having a series of tappets thereon for actuating said levers, and means for giving the shaft partial rotations to cause the pushers one at a time to eject a sole from the cabinet.

28. An apparatus for tempering soles and activating cement thereon comprising a cabinet provided with a plurality of stalls each adapted to support a sole edgewise, said cabinet having a well in its bottom arranged to hold water, means in the well for heating the water, means for forcing air through the water to heat the air and load it with water-vapor, means for varying the amount of water-vapor in the air, a pusher for each of said stalls, a lever connected to each of said pushers, a shaft having a series of tappets fixed thereto and extending from different positions radially of the shaft, and operator-controlled means for giving the shaft partial rotations to cause the pushers to eject the soles one at a time from the stalls in the cabinet.

HELGE GULBRANDSEN.
